UNITED STATES PATENT OFFICE.

JAMES H. CROCKWELL, OF SALT LAKE CITY, UTAH.

PORTABLE STOVE.

1,264,163.

Specification of Letters Patent. Patented Apr. 30, 1918.

Application filed July 10, 1917. Serial No. 179,698.

To all whom it may concern:

Be it known that I, JAMES H. CROCKWELL, a citizen of the United States, residing at Salt Lake City, in the county of Salt Lake 5 and State of Utah, have invented certain new and useful Improvements in Portable Stoves; and I do hereby declare the following to be a full, clear, and exact description of the invention, such as will enable others 10 skilled in the art to which it appertains to make and use the same.

This invention relates to a portable stove which is particularly designed to be inserted into the fire box of an ordinary cooking 15 stove through one of the openings in the top of the stove so that when it is desired to have only a small fire such as for heating gruel, or cooking any small article of food, a fire may be built in the portable stove for 20 creating the necessary or desired heat without building a fire in the entire stove.

A further object of this invention is to provide a portable stove as specified which is extremely simple in construction, being 25 formed of sheet metal, and which has a perforated bottom upon which a grate is supported, which grate is also perforated so as to permit of a draft upwardly through the bottom of the stove and the grate and also 30 to provide a cover ring or plate which rests upon the top of the sides of the stove and is detachably connected thereto by means of spring latches, which top is composed of a pair of hingedly connected sections.

35 With the foregoing and other objects in view, this invention consists in such novel features of construction, combination and arrangement of parts as will be hereinafter more fully described, illustrated in the accompanying drawing and claimed.

40 In describing the invention in detail reference will be had to the accompanying drawing wherein like characters designate like and corresponding parts throughout the several views, and in which—

Figure 1 is a detail perspective view of the improved portable stove,

Fig. 2 is a vertical sectional view through the stove showing the same inserted into an 50 ordinary stove, and

Fig. 3 is a section on the line 3—3 of Fig. 1.

Referring more particularly to the drawings, 1 indicates the main body of the portable stove which is constructed of sheet metal and is substantially cylindrical in

shape having its side 2 flattened. The sides of the body 1 taper or incline outwardly from the bottom 3 to the top of the stove and are rounded so as to provide a maximum interior space for the stove and also to shape the portable stove to fit the interior of an ordinary cooking range, the tapering of the sides and the flat side 2 being made necessary by the shape of the ordinary stove 60 grates. The base 3 of the body is provided with a plurality of perforations 4, which permit of an upward draft through the stove body.

A removable grate structure 5 is positioned within the stove body 1 and it has legs 6 formed upon the perforated base 7 thereof which legs engage the upper surface of the perforated bottom 3 of the body and holds the bottom 7 of the grate in 70 spaced relation to the bottom 3. The grate structure 5 has upstanding sides 8 which are constructed of the metal of which the grate is formed and are split as indicated at 9 so as to allow the upstanding sides of the 80 grate to be bent to conform to the configuration of the interior of the body 1. The flat side 2 of the body 1 is provided with an opening 10 formed near its upper end which allows for the escape of products of combustion from the auxiliary or portable stove into the main stove body indicated by the numeral 11 in Fig. 2 of the drawing.

The main body 1 of the stove has a ring 12 mounted upon its upper edge which ring 90 is composed of a pair of sections 13 and 14 which are hingedly connected as shown at 15. The ring structure 12 is removably mounted upon the top of the body 1 and it is held in proper place thereon by means of 95 spring clasps or catches 16 which have tongues 17 formed thereon. The tongues 17 extend through openings in the side of the body 1 as clearly shown in Fig. 2 of the drawings and they have their lower ends 100 rolled to form grips for springing them outwardly to remove the tongues 17 from the openings formed in the body, to permit the cover ring 12 to be removed or disconnected from the body 1.

The side 8' of the grate 5 extends above the upper ends of the remaining sides of the grate and it is provided with an opening 8^a formed therein for receiving any suitable implement which might be employed for 110 raising the grate out of the stove body for the purpose of cleaning the same. The grate

5 is smaller than the interior of the body 1 of the stove so as to allow free circulation of air about the same.

In the operation of the improved portable stove, when it is desired to make a small fire for heating a small article of food, or in warm weather when only a small fire is desired, the improved portable stove is inserted through one of the openings indicated 10 by the numeral 20 in Fig. 2 of the drawings, formed in the top of an ordinary cooking range, and a fire is started upon the grate 5 while the article to be cooked is placed over the opening in the ring 12, and with 15 the improved stove, the desired article may be heated or cooked by the utilization of a minimum quantity of fuel and without necessitating the building of a fire in the entire ordinary cooking range.

20 In reducing the invention in practice, certain minor features of construction, combination and arrangement of parts may necessitate alterations to which the patentee is entitled provided such alterations are comprehended within the scope of what is claimed.

Copies of this patent may be obtained for five cents each, by addressing the "Commissioner of Patents, Washington, D. C."

What is claimed is:—

A portable stove including a substantially cylindrical body having a perforated bottom, one side of said body being flattened and provided with an opening to permit the escape of products of combustion, a grate having a perforated bottom and upstanding sides, legs formed upon said grate bottom for holding said grate bottom in spaced relation to the body bottom, said grate being smaller than the interior of the body to permit air circulation about the grate, the sides of said body bulging outwardly toward the top thereof, a ring removably mounted upon the body and composed of a pair of hingedly connected sections, and means carried by said ring for engagement with said body to prevent accidental movement of the ring with respect to the body.

In testimony whereof I affix my signature in presence of two witnesses.

JAMES H. CROCKWELL.
